UNITED STATES PATENT OFFICE.

CHARLES W. KIRSCH, OF STURGIS, MICHIGAN.

DESIGN FOR A CURTAIN ROD OR SIMILAR ARTICLE.

Application filed July 9, 1925. Serial No. 14,034. Term of patent 14 years.

To all whom it may concern:

Be it known that I, CHARLES W. KIRSCH, a citizen of the United States, and a resident of Sturgis, county of St. Joseph, and State of Michigan, have invented a new, original, and ornamental Design for Curtain Rod or Similar Article, of which the following is a specification, reference being had to the accompanying drawings, forming a part thereof, wherein—

In Fig. 1, a complete curtain rod or similar article embodying the design is shown in perspective view and, in Fig. 2, a fragment thereof in rear elevation to bring out the decorative features more clearly.

I claim:

The ornamental design for a curtain rod or similar article as shown.

CHARLES W. KIRSCH.
